CLAIM

The ornamental design for absorber of electric noise, as shown and described.

DESCRIPTION

FIG. 1 is a perspective view of an absorber of electric noise showing my new design;

FIG. 2 is a front elevational view of thereof, the rear elevational view being the same;

FIG. 3 is a left side elevational view thereof, the right side elevational view being a mirror image;

FIG. 4 is a bottom plan view thereof drawn on an enlarged scale; and

FIG. 5 is a top plan view thereof.

FIG. 6 is a perspective view of a second embodiment of an absorber of electrical noise showing my new design;

FIG. 7 is a front elevational view thereof, the rear elevational view thereof being the same;

FIG. 8 is a left side elevational view thereof, the right side elevational view being a mirror image;

FIG. 9 is a bottom plan view thereof; and

FIG. 10 is a top plan view thereof.
